Primary Examiner — Rashida Johnson(74) Attorney, Agent, or Firm — Donald J. Ranft; Collen IP(57) CLAIM

The ornamental design for a shirt with front flap, as shown and described.

DESCRIPTION

FIG. 1 is a front right perspective view of a shirt with front flap showing my new design;

FIG. 2 is a front view thereof;

FIG. 3 is a rear view thereof;

FIG. 4 is a left side view thereof;

FIG. 5 is a right side view thereof;

FIG. 6 is a reduced front view of my new design shown on a person thereof;

FIG. 7 is a reduced front view of my new design shown on a person with flap lifted thereof; and,

FIG. 8 is a front right perspective view with flap partially raised.

The portions of the drawings shown in broken lines form no part of the claimed design.
